UNITED STATES PATENT OFFICE.

GEORGE J. WEBER, OF BOONVILLE, MISSOURI.

WHEELED SCRAPER.

SPECIFICATION forming part of Letters Patent No. 245,898, dated August 16, 1881.

Application filed January 31, 1881. (No model.)

To all whom it may concern:

Be it known that I, GEORGE J. WEBER, a citizen of the United States, residing at Boonville, in the county of Cooper and State of Missouri, have invented Improvements in Wheeled Scrapers, of which the following is a specification.

The machine consists of a scoop or scraper of any suitable form, having near its front end 10 hangers pivoted to arms projecting from a curved axle-beam, and capable of being connected or disconnected in the rear at will, by means of a hook extending from the back of the scoop, and a gravitating loop pivoted to a hand-lever projecting rearwardly from said axle-beam. Extending laterally from the axle-beam are two detachable gudgeons upon which 15 rotate the two supporting-wheels. The apparatus is provided with a tongue to which are 20 attached two draw-bars pivoted to the sides of the scoop, near its front, at the base of the aforesaid hangers, and having upon their rear ends lugs or stops, which, impinging against the back of the hangers, prevent the scoop 25 from tilting backward beyond a certain limit. Attached rigidly to the tongue is an upwardly-projecting spring-arm, having near its upper end an eye in which a pin on the hand-lever automatically engages when the scoop is inverted, so as to hold the scoop in that position, 30 if desired, until it is to be refilled, when it may be released by a pull sidewise upon the spring-arm. Inside the scoop is a rectangular plate pivoted at its back corners to the sides of the 35 scoop, and capable of being operated at will by a lever outside the scoop, the object being to assist the team in filling the scoop and compressing the earth, and also to prevent the earth from falling out during transportation. 40 A catch or projection on the side of the scoop holds the said lever in its depressed position. Besides the hand-lever referred to, two handles, one on each side of the scoop, are provided, which are also used in operating the 45 scraper. Secured to the under side of the scoop are two runners of I-shaped cross-section, which are cast with a chilled base and riveted to the scoop by their upper flanges, thus making no obstruction on the wearing-surface, and also 50 preventing the rivets being worn off by abrading sand, gravel, &c.

In order that my invention may be fully understood, I will proceed to describe the same with reference to the accompanying drawings, in which—

Figure 1 is a perspective view of a wheeled scraper embodying my improvements. Fig. 2 is a side elevation of the same, showing the scoop in its inverted position. Fig. 3 is a perspective view of one of the runners. Fig. 4 60 is a perspective view of part of the scoop, showing the hinged plate. Fig. 5 is a perspective view of one of the gudgeons detached.

A A are two ground-wheels supporting the axle beam or yoke B and the apparatus hung thereto, by means of detachable gudgeons C, that being partly embedded in the frame B are secured thereto by U-shaped clamps D and nuts d.

The object of making the gudgeons detachable is to enable the changing of the machine from a wheeled to a sliding scraper by removing the gudgeons and wheels, which may be done by simply unscrewing the nuts d d and slipping out the clamps D D.

The two arms E E of the yoke B extend forward of the gudgeons to a point, e, immediately over the coupling F of the tongue or draw-bars G G to the scoop H, at which point e they are pivoted to hangers I I, that extend downward therefrom to the aforesaid coupling, F, and then upward again on the inside of said tongue-bar, where they are firmly secured by rivets or bolts i i to the sides of the scoop H.

The axle beam or yoke B is curved backward 85 from the gudgeons, and to its middle portion is rigidly secured a hand-lever, J, that extends sufficiently to the rear to give the desired leverage. Pivoted to this hand-lever, at k, is a gravitating loop or dog, K, adapted to engage 90 under a beveled hook, L, on the back of the scoop. An arm, k', on the loop K enables the operator to release the same from the hook L when it is desired to lower the scoop to the ground.

The tongue-bars G G converge toward and are attached to the tongue M at m at which point also is attached an L-shaped arm, N, that extends upward and slightly backward, and is provided near its upper end with an 100 eye, n, and handle n'. When the scoop is inverted, and the hand-lever J shoved forward

as far as possible, a pin or stud, O, on said hand-lever, sliding along the inclined surface n'' , immediately above the eye n , and thereby pushing slightly to one side the arm N, (which is made with sufficient spring for the purpose,) engages within said eye, and thus holds the scoop in its inverted position, as shown in Fig. 2.

It will be observed that, owing to the loop form of hangers I I and curved shape of the axle-beam B, the tongue-bars G G are free to turn on pivots F F into a position back of the gudgeons C C, as shown in Fig. 2. The rear ends of the tongue-bars G G extend upward from the coupling-pivots F F, as at R, and at the extremities of such extensions are lugs or stops r, which, by impinging against the back of the hangers I I, serve to prevent the scoop tilting backward when loaded.

In the inside of the scoop is a plate, P, pivoted at $p p$ to the sides of the scoop and having a lever or levers, Q, rigidly attached to one or both of its pivots. The use of this plate is to assist in the loading of the scoop when in its depressed position and to prevent the earth from falling out during transportation when elevated by depressing the lever Q. A beveled catch or hook, S, on the side of the scoop beneath which the lever may be forced, serves to hold said lever in its depressed position.

On each side of the scoop are rigidly attached handles or arms T, used in guiding the scoop into and out of the ground. These handles pass through the back of the scoop and at their forward ends are riveted or bolted to the backwardly-projecting arms I' I' of the hangers I I.

Riveted or bolted to the under side of the scoop are two cast runners, U, of I-shaped cross-section, which have their lower flanges, u, chill-hardened, and through whose upper flanges, u', pass the rivets or bolts h. The lower flanges, u, are curved upwardly in front to meet the bottom of the scoop, as shown. By this construction of runner none of the rivets or bolts form any part of the abrading or sliding surface, and hence the said surface remains smooth and unbroken.

The scraper is operated as follows: The operator, releasing the dog K, allows the scoop to gouge into the earth until nearly filled; then, pushing downward on lever Q, the earth is thrown into the back of the scoop, the power of the team assisting in the operation by causing the earth in front of the plate to press the same backward; then, depressing the hand-lever J, the dog K engages automatically under the hook L, and the load, being

then supported wholly upon the wheels, may

be transported to its destination without unnecessary loss of power. In order to dump the load the operator throws the hand-lever J forward a sufficient distance to invert the scoop and thus discharge it. By shoving the lever forward until the pin O engages in the eye n the scoop will be held securely in its inverted position, and may remain so during transportation. The plate P, which remains depressed while the scoop is filling, is tipped up when the scoop is full in order to prevent any earth falling out. For this purpose the lever Q is pushed down below catch S, from which it is again released when the load is to be discharged.

I am aware that it is not new to construct vehicles with detachable gudgeons, and such I do not wish to claim *per se*, as my invention in this particular consists in adapting a scraper to be readily converted into either a wheeled or sliding scraper at will.

Having thus described my invention, the following is what I claim as new therein and desire to secure by Letters Patent:

1. The combination, with the scraper-body, of the axle-beam B and detachable gudgeons C C, the latter secured to the former, as set forth.

2. The combination, in a wheeled scraper, of the curved axle-beam B, hand-lever J, and hangers I I for raising, lowering, and supporting the front part of the scoop.

3. The combination, in a wheeled scraper, of the hand-lever J, axle-beam B, with the dog K, hook L, and hangers I I, substantially as and for the purpose set forth.

4. In a wheeled scraper, the combination of the curved axle-beam B and looped hangers I I, pivoted thereto, with the tongue M and tongue-bars G G, pivoted at the lower end of said hangers, operating as set forth.

5. In a wheeled scraper, the gravitation-loop K, pivoted to the supporting-frame and having arm k', in combination with beveled-hook L on the scoop, for the purposes set forth.

6. The combination of looped hangers I I and pivoted tongue-bars G G, having stops r, all operating as and for the purpose set forth.

7. The hinged plate P and its operating-lever Q, in combination with catch S, as and for the purpose set forth.

8. The cast runners U, of I-shaped cross-section, as and for the purpose set forth.

9. The combination of the handles T, passing through the back of the scoop and secured at their forward ends to the backwardly-projecting arms I' I', of the hangers I I, as and for the purpose set forth.

GEO. J. WEBER.
